WHEEL CHAIR

Sanford S. Golden, West Los Angeles, Calif.

Application July 5, 1957, Serial No. 46,840

Term of patent 14 years

(Cl. D15—11)

Fig. 1 is a perspective view of a wheel chair showing my new design, the wheel chair being viewed from the left side and front and illustrating the leg portion in an extended position;

Fig. 2 is another perspective view thereof, the wheel chair being viewed from the right side and front and being in a downwardly inclined position and illustrating the leg portion in a folded position; and

Fig. 3 is a rear elevational view, on a reduced scale, of the wheel chair.

I claim:

The ornamental design for a wheel chair or similar article, substantially as shown.
